UNITED STATES PATENT OFFICE.

FREDERICK J. GEIGER AND ANTHONY ELTON DAVIS, OF PHILADELPHIA, PENNSYLVANIA.

VAULT- SKY- OR FLOOR-LIGHT CONSTRUCTION.

1,245,214.

Specification of Letters Patent.

Patented Nov. 6, 1917.

Application filed May 5, 1916. Serial No. 95,564.

To all whom it may concern:

Be it known that we, FREDERICK J. GEIGER and ANTHONY ELTON DAVIS, both citizens of the United States, and residents of Philadelphia, in the county of Philadelphia and State of Pennsylvania, have invented a new and useful Vault- Sky- or Floor-Light Construction, of which the following is a specification.

10 The principal objects of the present invention are to provide a construction for vault- floor and sky-lights, the principal parts of which can be made in the advantageous conditions of a shop or factory and 15 carried in stock as a sort of unit, multiples of which can be readily assembled on the ground with the other parts of the construction so as to meet the requirements of practically any job or piece of work. Another 20 object of the invention is to provide for minimizing the work that is done at the place of construction or assemblage. Another object of the invention is to effect an economy in the depth of the glass. Another object of 25 the invention is to provide a strong, attractive and slightly construction of the kind referred to which can be made and assembled in a simple, expeditious and comparatively inexpensive way of erecting or making 30 such constructions.

The invention will be claimed at the end hereof, but will be first described in connection with the accompanying drawings, forming part hereof and illustrating an embodiment of the invention chosen from other embodiments, and in which—

Figure 1, is a top or plan view with parts removed illustrating a construction embodying the invention and also the method of 40 construction.

Fig. 2, is a transverse section of Fig. 1.

Fig. 3, is a view drawn to an enlarged scale and illustrating a section taken at right angles to the plane of Fig. 2.

Fig. 4, is a top or plan view of one of the open bottom cups, and

Fig. 5, is a sectional view of the same showing in dotted lines features of construction.

50 The unit of the construction consists of an open bottom cup 1 having a glass receiving opening 2 and a flaring channel forming base 3. The opening 2 is shown as rectangular so as to accommodate a rectangular glass 4, but it may be made circu-

lar or of any other form to conform to the shape of the glass. The portion 3 flares externally so as to form a channel as will be described and it may flare internally as shown, and when it does it enlarges the 60 space for the passage of light. 5 is a flange encircling the cup and when it is present it operates as a retaining means. It has been said that the opening 2 may be circular or of any appropriate shape, but the flaring 65 base should be rectangular so that when a number of cups are assembled their bases may contact with each other thus closing the bottoms of the channels 6 and giving one face of the construction a neat and slightly 70 appearance. The cups can be made in a factory and under appropriate conditions for attaining the best results. When finished they may be carried in stock so that the work can be made continuous instead of seasonal. If desired the inner portion of the 75 cups can be finished or burnished so as to present an attractive appearance since they constitute one face of the construction and if desired a suitable pigment or coloring 80 matter can be incorporated so that the cups may be colored and when this is done they may be arranged after the fashion of mosaics to produce appropriate designs.

In the completed structure an appropriate 85 number of cups for covering the opening are arranged with their flaring bases in contact, thus forming intersecting channels 6 having substantially closed bottoms. Reinforcements 7 and 8, as metal rods of deformed cross-section are arranged in crossed relation in the channels 6. Glasses 4 are mounted in the cups and seated on the tops thereof. For this purpose the glasses may be formed with projections 9 adapted to fit 95 in the top of the cups and so center and properly hold the glasses against lateral or other motion in respect to the cups and since the rectangular bases of the cups are in contact with each other the cups are held 100 against sidewise displacement. Concrete 10 is applied in the channels 6 and around the glasses and cups and reinforcements and is permitted to set and adhere to those parts, while it is confined by the closed bottoms of 105 the channels. The concrete is struck off level with the faces of the glasses and with them constitute one face of the construction, the other face of the construction is made up of the interior portions of the cup and one of 110

the faces of the glasses. Since the bases of the cups abut as at 11, no concrete is visible and the abutment is so close that the line of contact is scarcely visible.

5 During the erection of the construction it is necessary to employ some kind of temporary structure upon which to place the cups, and a description of one such temporary structure will be given.

10 The members 12 and 13 are assumed to be the supports upon which the structure is to be erected. 14 are lintels that constitute a part of the permanent structure and they are arranged to span and rest upon the

15 members 12 and 13. They may be variously constructed, as for example, of reinforced concrete or they may be rolled metal bars of suitable cross-section. It is well to have their faces 15 covered because those faces

20 are exposed between certain of the cups and therefore they should match the cups in order to obtain the best effects. These lintels may be carried in stock lengths and they are easily cut to fit structures in which the distance between the supports 12 and 13 is

25 anything short of their lengths. When the lintels are provided with tapped sockets, hangers 16 may be employed to support the temporary structure 17 upon which the cups

30 and other parts are assembled. The members of the temporary structure 17 may consist of boards of sizes appropriate to fit them for use in making structures of different sizes. A section of the structure can be

35 readily leveled and brought to conform to the adjacent level by wedging up the lintels in respect to the supports 12 and 13 as may be necessary. The finished structure is not only supported by the lintels but also by the

40 supports 12 and 13 since the concrete 10 and reinforcements can extend over both of them. The hangers 16 and temporary structure can be assembled from the top, the keys 18 permitting of the application of the elements 19. This is frequently a matter of

45 some convenience. 20 are side pieces which can be laid on top of the lintels if desired and which when present, together with the parts 21, make up a sort of frame in which a

50 section of the structure can be assembled and the parts 20 can be removed, leaving a space that can be used in providing an expansion joint between the sections, or if desired the layer of concrete 10 can be ex-

55 tended continuously across the lintels as is indicated in the upper left-hand portion of Fig. 1.

In the finished structure the cups are well

held in the layer of concrete not only by adhesion but also by the retaining flanges 5, 60 when present, and the whole structure including the cups, glasses and reinforcements and lintels might well be described as a reinforced monolith.

It will be obvious to those skilled in the art that modifications may be made in details without departing from the spirit of the invention, which is not limited as to those matters or in any way other than as the prior art and the appended claims may require.

What we claim is:

1. A vault- sky or floor light construction consisting of the combination of cups open top and bottom and having the lower portions thereof in contact with each other and other portions out of contact with each other forming channels, glasses mounted on the cups and extending above the same, and concrete filling the channels and contacting with the glasses above the cups and binding said parts into the complete structure. 75

2. A vault- sky or floor light construction consisting of the combination of peripherally flanged cups open top and bottom and having portions thereof in contact with each other and other portions out of contact with each other forming channels, glasses mounted on the cups and extending above the same, and concrete filling the channels and 80 engaging the flanges and contacting with the glasses above the cups and binding said parts into the completed structure. 85

3. A vault- sky or floor light construction comprising the combination of supports, lintels spanning the supports, cups open top and bottom and having flaring bases in contact with each other forming channels, reinforcements arranged in the channels and overlying the lintels and supports, and concrete filling said channels and embracing said reinforcements and cups and extending above the cups into contact with the glasses, 95 substantially as described. 100

4. A vault- sky or floor light construction 105 consisting of the combination of cups open top and bottom and having flaring bases in contact with each other forming channels and constituting a permanent face of the construction, glasses mounted on top of said 110 cups, reinforcements in said channels, and concrete filling the channels and contacting with the cups and reinforcements and glasses.

FREDERICK J. GEIGER,
ANTHONY ELTON DAVIS.
